UNITED STATES PATENT OFFICE

GEORGE SPATTA, OF BUCHANAN, MICHIGAN, ASSIGNOR TO CLARK EQUIPMENT COMPANY, OF BUCHANAN, MICHIGAN, A CORPORATION OF MICHIGAN

THROAT FORMING MACHINE AND METHOD

Application filed February 10, 1930. Serial No. 427,804.

This invention relates to a throat forming machine and method.

In the manufacture of rear axle housing in accordance with the teachings of my copending application, Serial No. 416,537, filed December 26, 1929, a tubular blank is slotted at its lower mid-section, its end sections are then reduced to cylindrical sections of smaller diameter, the mid-section is spread and shaped to form a flanged cylinder disposed transversely of the cylindrical end section. These operations, described more fully in my above mentioned copending application, leave the metal at the so-called throat, or junction of the small diameter end cylinder and the transversely disposed central cylinder in rough and unshapely form.

The operation of reducing the diameter of the end section of the blank is effective to form a taper at the throat section, leaving the portion of that section adjacent the transverse cylindrical portion of the same diameter as the original blank.

The central section or banjo is flanged and formed in the manner fully disclosed in my copending application, Serial No. 426,545 filed February 7, 1930. This operation forms the banjo into a web and flanges, the web being shorter than the diameter of the original blank from which the housing is made. As a result, the banjo forming operation leaves a bulge at the junction of the banjo and end sections of the housing, and also leaves irregular surfaces at the junction of the web of the banjo and the walls of the cylindrical end sections. The throating operation removes this bulge by pressing the metal inward of the housing and also removes the irregularities between the web and end cylinders by pressing the metal outward. The preferred method of carrying out this forming performs the two operations simultaneously.

In the present application, I disclose a machine for and method of forming this throat section to produce smooth and graceful lines joining the cylindrical end sections of the housing to the transversely disposed central section or banjo.

The preferred form of machine employed

to carry out the objects of the instant invention comprises a horizontal cylinder from which a strain rod is projected horizontally between the side rails of the machine, and a die is disposed on these side rails with its axis coinciding with the axis of the strain rod.

The die is stationary and has interior surfaces formed to the shape that it is desired to shape the exterior surfaces of the finished throats. The rod projects through the die, and is equipped with a suitable end for attaching a punch to the rod.

The punch is a unitary block of wedge-shape generally, which has exterior surfaces conforming to the desired shape of the interior surfaces of the throats, and is provided with a flat back face, that is, a face on the side away from the die, against which a clamping device for holding the punch on the rod exerts a pressure to force the punch and the blank into the die.

In the operation of this machine, the blank is threaded over the strain rod, the punch fitted inside of the banjo of the blank and over the strain rod, the punch is clamped to the strain rod, and the rod then moved to move the blank and the punch into the die to perform the throat forming operation.

In the preferred embodiment of the machine, the rod is moved by hydraulic means, although any other suitable arrangement for moving the rod may be employed within the teachings of my invention.

When the throat forming operation has been completed, the rod movement is reversed, and a collar and shoulder on the rod thus brought into operation, force the blank and punch out of the die to permit them to be disassembled and removed from the machine.

The horizontal location of the strain rod and consequent horizontal positioning of the blank during the throat forming operation facilitates forming the operation at a maximum speed with a minimum of labor, since the attendant of the machine can lay the blank on the flat horizontal table portion of the machine, and thread it over the strain rod while it is still supported by the table of the machine. This eliminates the necessity of

lifting the blank, which weighs approximately forty pounds, during the threading operation, with the result that a single operator can quickly and conveniently insert 5 the blank in the machine and operate it to perform the throat forming operation.

Now, to acquaint those skilled in the art with the teachings of my invention, reference is made to the accompanying drawings 10 in which the preferred embodiment of it is shown by way of example and in which:

Figure 1 is a plan view of a completely assembled machine with a blank in place in the die;

15 Figure 2 is an elevational side view of Figure 1;

Figure 3 is a cross-sectional elevation view taken along the line 3—3 of Figure 1;

20 Figure 4 is a cross-sectional view taken substantially along the line 4—4 of Figure 2, drawn to an enlarged scale;

Figure 5 is an enlarged scale sectional elevation view through the die taken along the line 5—5 of Figure 4, looking in the direction 25 of the arrows;

Figure 6 is a detailed end view of the punch and die taken substantially along the line 6—6 of Figure 5, looking in the direction of the arrows;

30 Figure 7 is a cross-sectional view through the die with the blank and punch removed, showing the details of its construction and method of attaching it to the frame of the machine;

35 Figure 8 is a cross-sectional view through the strain rod taken along the line 8—8 of Figure 5, showing the details of the blank removing collar on the rod; and

40 Figure 9 is a perspective view of the blank after it has been formed by the machine.

Referring to the drawings now, in more detail, the machine comprises a frame consisting of side rails 1 and 2 to one end of 45 which is attached a cylinder head 3, by the bolts 9. The rails 1 and 2 may conveniently be cold rolled steel of suitable size and having a generally rectangular cross-section, or if preferred, channels, I-beams or angles may 50 be used.

The side members and cylinder head of the frame are supported on suitable cast iron legs 4, 5 and 6, to bring the working surface 55 of the machine at a height at which a workman may conveniently place the blanks in the machine with a minimum effort. The side rails 1 and 2 are provided with a shouldered portion 7 and a shouldered portion 8, which together, form a pocket or seat in 60 which the die structure is placed. That portion of the rail members 1 and 2 which extends beyond the die may be narrower than the sections between the die and the cylinder head 3, since this portion merely 65 acts as a table upon which the blanks are

placed when they are being inserted in the die.

Cylinder 10 is abutted against the outside surface of the cylinder head 3, and provided with a cylinder head 11, which is held against the opposite end cylinder 10 by external bolts 12 which are threaded into the cylinder head 3 and projected through the head 11. This arrangement puts the walls of the cylinder 10 under compression normally to thereby better enable them to withstand the stresses imposed upon them when pressure is built up within the cylinder, and while this arrangement is preferable, any other form of cylinder may be substituted. 75

The cylinder is provided with a piston 13 which has a piston rod 14 projecting through the cylinder head 3 and packing gland 15 disposed therein, and terminating in a coupling member 16 to which it is adjustably connected by the threaded portion 17, and locked by the collar 18 threaded onto the threaded portion 17 and abutting against the end of the coupling 16. 80

The cylinder head 11 is provided with a port 19 through which pressure is admitted to move the piston to the right, Figure 3, and the cylinder head 3 is provided with a port 20, through which pressure is admitted to the reverse side of the piston 11 to move it to the left, Figure 3. Any suitable means may be employed to generate this pressure, and therefore the pressure pumps have been omitted from the drawings to avoid an unnecessary complication of them. 90

The admission of fluid pressure through ports 19 and 20 is controlled by the valve 21 which may be any preferred type of control valve that is operable when the rod 22 is moved in one direction to admit pressure through the port 19 and operable when the rod 22 is moved in the opposite direction to admit pressure through the port 20. 95

The rod 22 is connected by a suitable bell crank 23 to a cross rod 24 which terminates in a lever 25 on the front or operating side of the machine, which lever is operated in one or the other direction to control the movement of the piston 13 in the cylinder. 105

The die structure comprises a pair of rectangular blocks 30 and 31 which are bolted together by bolts 32 and held on the frame of the machine in any suitable manner, such as by the bolts 33, which are projected through a holding plate 34 and threaded into the plate 31. 115

The interior surfaces of the die blocks 30 and 31 are cut away to form the contour of the outside of the finished throat as will best be seen at 35 in Figures 4 and 7. Suitable guide wedges 36 are attached to the frame adjacent the open end of the die by bolts 37, these wedges serving to guide the work into the die during the operation of the machine. 125

In the forming of the throat section of an 130

5 axle housing, the maximum wear on the die occurs at its upper and lower surfaces which are forced over the bulges at the throat sections of the blanks to press the metal in these bulges inward into the desired shape. To minimize the wear upon the die as much as possible, I have provided hardened die plates 40 and 41 which are fitted into suitable depressions 42 and 43 in the open face of the die, and held therein by stud screws 44 and 45 respectively, which are threaded through the die block and into but not through the hardened die plates.

10 The frictional wear imposed upon these plates by the movement of the blanks into and out of the die, causes them to wear somewhat, and when their surfaces become roughened and tend to tear the blanks, the blocks can be removed and resurfaced in any convenient manner, as by grinding, after which they are replaced in the machine with shims interposed between the plates and die blocks 30 and 31 to maintain the working surfaces of the plates 40 and 41 at a proper distance 25 from each other.

15 A strain rod 50 is attached to the coupling 16 on the end of the piston rod 14 by a threaded connection 51, and the rod projected through the central portion of the die 30 with its axis coinciding with the axis of the die. A tubular sleeve 52 is fitted over the end of the strain rod 50 adjacent the coupling 16 and held thereon by a flange 53 which is bolted to the coupler by bolts 54 and to 25 which the sleeve is bolted by bolts 57. The outward end of this sleeve 52 is provided with shouldered portions 55 and 56 which are spaced away from the rod 50 a slight distance for a purpose which will be hereinafter explained.

30 The rod 50 is also provided with a shoulder 58 which is located at a point on the rod 50 that is disposed within the die, and the end section of the rod projecting beyond this shoulder is of slightly smaller diameter.

35 The punch 60 is provided with a centrally located opening 61 which registers with the small diameter portion 62 of the rod 50, where it is held in place on the rod by the clamp 63 which fits into the slot 64 in the end section 50 of the rod.

40 The clamp 63 comprises two semicircular plates joined together by a U-spring 65, the tension of which holds the plates in place in the slot 64 on the shaft. A hardened batter plate 66 is attached to the flat face of the punch 60 adjacent the clamp 63 and held thereon by screws 67, to thereby enable the punch to resist the wear placed on it by the hardened clamping plates 63 which bear against that face. The plate 66 is provided with a handle 68 which facilitates insertion and removal of the punch from the die and rod.

45 In the operation of the machine, the blank

70 is laid on the end portions of the frame members 1 and 2, and its cylindrical end section 71 extended over the free end of the strain rod 50. The outside diameter of the larger portion of this rod 50 accurately fits the inside diameter of the end section 71 of the blank to thereby keep the blank straight during the throat forming operation performed by the machine. The punch 60 is then placed within the banjo section 72 of the blank and the small diameter portion 62 of the pull rod inserted through the opening 61 in the punch. Clamp member 63 is then inserted in place in the slot 64, and the die and punch structure is in readiness for an operation of the machine.

75 The control lever 25 is operated to cause pressure to be built up in the cylinder 10 to move the piston 13 to the left, as seen in Figure 3, this movement pulling the strain rod 50 and punch 60 carried thereby to the left. The punch engages the inner surfaces of the blank and carries the blank into the die where the bulges are removed and the wall sections of the blank altered to a shape conforming to the outside surface of the punch and inside surfaces of the die.

80 It will be noted that the blank is cold during this step in the process of forming the rear axle housings, and also noted that the amount of metal to be shifted in the forming of the throat is so small that it can be successfully formed while cold.

85 As will be seen in Figure 5, the bulges 73 and 74 at the junction of the cylindrical end sections and banjo portions of the housing will be flattened out when the flange is forced into the die. The metal in these bulges 73 and 74 travels into the flanges 76 and into the side wall sections 77 which are interposed between the two bulges. These side wall portions 77 are to be pushed outward by the operation of the punch 60, and the metal which they receive from the bulges 73 and 74 permits this to be performed without undue stretching of the walls of the blank.

90 When the piston 13 has completed its travel and the punch 60, the blank 70 and rod 50 are fully positioned within the die, this being insured by the adjustment of the coupling 16, the lever 25 is operated in the reverse direction and the piston 13 thereby operated to move the rod 50 in the opposite direction. This brings the shoulder 58 on the rod against the innermost surface of the punch, thereby permitting the rod to push the punch out of engagement with the die and blank. As the rod 50 is moved through the die, the shouldered portions 55 and 56 of the collar 52 engage the end section 71 of the blank, and as the rod is moved, push that section out of the die in the obvious manner.

95 When the piston 13 has completed its travel, clamps 63 are removed from the groove 64 and the punch 60 removed from the end

portion 62 of the rod 50, and from the blank 70. If the opposite end of the blank has not as yet been formed, the blank is turned end for end on the machine, the punch reinserted 5 and locked on the rod 50 and the operation repeated to form a throat at the opposite end of the blank. After both ends of the blank have been thus formed, it is lifted from the machine and another substituted for it and the 10 operation repeated.

From the foregoing it will be apparent that the operation of the machine is extremely simple and since the blanks are placed upon the flat horizontal portion of the machine 15 prior to being threaded over the strain rod 50, and since this portion of the machine is at a height at which the workman can conveniently manipulate the blanks, the threading of the machine is an extremely simple 20 operation which can be carried on by one man without undue fatigue. The horizontal arrangement of the elements of the machine permits me to gain this advantage.

Since the strain rod 50 is under tension during 25 its work performing movement, and since the reactions set up in the cylinder by the pressure that causes this movement and by the die in resisting the movement, are in the opposite direction to the frame members 1 and 2 are placed under compression between the die and the working cylinder and since 30 metals are stronger under compression than under tension, the frame members may therefore be made smaller and lighter, and an appreciable saving in floor space may thereby 35 be realized.

While I have chosen to show my invention, by illustrating a preferred embodiment of it, I have done so by way of example only as 40 there are many modifications and adaptations which can be made by one skilled in the art without departing from the teachings of the invention.

Having thus complied with the statutes and 45 shown and described a preferred embodiment of my invention, what I consider new and desire to have protected by Letters Patent is pointed out in the appended claims.

What is claimed is:—

50 1. The method of forming the throat which joins the small diameter cylindrical end section of an axle housing with the transversely disposed flanged cylindrical midsection, which comprises, pushing wall sections of the 55 throat inward to form a smooth junction between the flanged face of the midsection and the end section and pushing other wall sections of the throat outward to form a smooth junction between the outer surfaces of the 60 transverse and end section cylinders.

65 2. The method of forming the throat which joins the small diameter cylindrical end section of an axle housing with the transversely disposed flanged cylindrical midsection, which comprises, pushing wall sections of the

throat inward to form a smooth junction between the flanged face of the midsection and the end section and simultaneously pushing other wall sections of the throat outward to form a smooth junction between the outer surfaces of the transverse and end sections cylinders. 70

3. The method of forming the throat section of a banjo type axle housing which comprises the following steps, viz., threading the 75 end section of the housing over a strain member and through a forming member, placing a pusher in the banjo of the housing and on the strain member, locking the pusher on the strain member, pulling on the strain member 80 to push the housing into the forming member to form it, pushing on the strain member to remove the housing from the forming member, and removing the pusher and housing 85 from the strain member.

4. In a machine for shaping the junction of a cylindrical end section with a transverse cylindrical midsection of a blank, a die into which the blank is inserted and through which said end section projects, a rod projecting through said blank and die, a shoulder on the rod, a collar on the rod, a punch, means for holding the punch on the rod, means for moving the rod to bring the punch into registration with the blank and die to 90 form the blank, and means for reversing the movement of the rod, to cause said shoulder to push the punch and said collar to push the blank out of the die. 95

5. In a machine for shaping the junction 100 of a cylindrical end section with a transverse cylindrical midsection of a blank, a die into which the blank is inserted and through which said end section projects, a rod projecting through said blank and die, and accurately fitting the inside surface of the cylindrical end section of the blank to keep 105 that section straight while the blank is in the machine, a shoulder on the rod, a collar on the rod, a punch, means for holding the punch on the rod, means for moving the rod to bring the punch into registration with the blank and die to form the blank, and means for reversing the movement of the rod, to cause said shoulder to push the punch and 110 said collar to push the blank out of the die. 115

6. In a machine for shaping the junction of a cylindrical end section with a transverse cylindrical midsection of a blank, a die into which the blank is inserted and through which said end section projects, a rod projecting through said blank and die, a shoulder on the rod, a collar on the rod, the end of which forms a second shoulder disposed adjacent the free end of the end section of 120 said blank, a punch, means for holding the punch on the rod, means for moving the rod to bring the punch into registration with the blank and die to form the blank, and means for reversing the movement of the rod, to 125 130

cause said shoulder to push the punch and said collar to push the blank out of the die.

7. In a machine for shaping the junction of a cylindrical end section with a transverse cylindrical midsection of a blank, a die into which the blank is inserted and through which said end section projects, hardened inserts in said die, a rod projecting through said blank and die, a shoulder on the rod, a collar on the rod, a punch, means for holding the punch on the rod, means for moving the rod to bring the punch into registration with the blank and to move the blank over said hardened inserts and into registration with the die to form the blank, and means for reversing the movement of the rod, to cause said shoulder to push the punch and said collar to push the blank out of the die.

8. A forming machine comprising a stationary die, a pull rod projecting through the center of the die and extending therebeyond, a shoulder on the free end of the said rod, a punch positioned on said rod between said shoulder and die, means registering with said shoulder for preventing movement of said punch toward the free end of said rod, and means for moving the rod through the die to bring the punch into registration therewith.

30 9. A forming machine comprising a stationary die, a pull rod projecting through the center of the die, and extending therebeyond, a shoulder on the free end of said rod, a punch positioned on said rod between said shoulder and die, means registering with said shoulder for preventing movement of said punch towards the free end of said rod, said means permitting unlimited rotation of the punch on said rod to align it with said die, 40 and hydraulic means for moving the rod through the die to bring the punch into registration therewith.

10. A forming machine comprising a stationary die, a pull rod projecting through the center of the die, and extending therebeyond, a shoulder on the free end of said rod, a punch positioned on said rod between said shoulder and die, a clamp registering with said shoulder for preventing movement of said punch toward the free end of said rod, and means for moving the rod through the die to bring the punch into registration therewith.

11. A forming machine comprising a stationary die, a pull rod projecting through the center of the die, and extending therebeyond, a shoulder on the free end of said rod, a punch positioned on said rod between said shoulder and die, a clamp comprising two crescents registering with said shoulder for preventing movement of said punch toward the free end of said rod, and means for moving the rod through the die to bring the punch into registration therewith.

12. A forming machine comprising a stationary die, a pull rod projecting through the

center of the die, and extending therebeyond, a shoulder on the free end of said rod, a punch positioned on said rod between said shoulder and die, a clamp comprising two crescents registering with said shoulder, a spring for holding said crescents together on said rod for preventing movement of said punch toward the free end of said rod, and means for moving the rod through the die to bring the punch into registration therewith.

13. A forming machine comprising a stationary die, a pull rod projecting through the center of the die, and extending therebeyond, a shoulder on the free end of said rod, a punch positioned on said rod between said shoulder and die, a clamp comprising two crescents registering with said shoulder, a U-shaped spring for holding said crescents together on said rod for preventing movement of said punch toward the free end of said rod, and means for moving the rod through the die to bring the punch into registration therewith.

14. A forming machine comprising a stationary die, a pull rod projecting through the center of the die, and extending therebeyond, a shoulder on the free end of said rod, a punch positioned on said rod between said shoulder and die, a clamp comprising two crescents registering with said shoulder, a spring for holding said crescents together on said rod for preventing movement of said punch toward the free end of said rod, and hydraulic means for moving the rod through the die to bring the punch into registration therewith.

15. A forming machine comprising a stationary die, a pull rod projecting through the center of the die, a shoulder on said rod having a radial face toward the free end of the rod, a second shoulder on the rod having a radial face toward the die end of said rod, a punch on said rod between said shoulders, means for moving said rod through said die in both directions, and means including said shoulder for causing the movement of the rod to move the punch in and out of the die.

16. A forming machine comprising a stationary die, a pull rod projecting through the center of the die, a shoulder on said rod having a radial face toward the free end of the rod, which free end is of smaller diameter than the rest of the rod, said free end having an annular groove which forms radial shoulders that oppose each other, a punch having an opening through which the smaller diameter portion of said rod is fitted to position the punch on the rod between said first shoulder and said groove, a clamp registering with said groove to hold the punch on said rod, and means for moving said rod longitudinally through the die, said groove and clamp moving the punch into the die with the movement of the rod in that direc-

tion and the first shoulder moving the punch out of the die with the movement of the rod in the opposite direction.

17. A throating machine for forming axle 5 housings of the banjo type comprising a die having forming surfaces shaped to the contour of the outer surface of the throat section of a finished housing, a punch shaped as the interior shape of the throat section 10 of the housing and having a hole disposed with its axis coinciding with axis of the die, a pull rod projecting through the die and through the punch, a clevis for locking the rod to the punch, and means for moving the 15 pull rod to bring the punch into registration with the die.

18. In a throating machine, a frame, a cylinder mounted thereon with its axis horizontal, a die mounted on said frame so that 20 the axis of the cylinder coincides with the axis of the die, a piston in the cylinder, a rod projected through the die and adjustably connected to the piston, a punch carried by the rod, and means on said frame for admitting pressure to said cylinder to cause it 25 to move the piston and thereby move the punch into registration with the die.

19. In a throat forming machine, a pair 30 of members of rectangular section terminating in a cylinder head whose face is at right angles to the faces of members, shoulders formed in said members parallel to said head face to reduce the ends of the members opposite the head to smaller dimensions, a die 35 mounted on the frame against said shoulder, a cylinder mounted on said cylinder head with its axis in alignment with the axis of said die, a rod projecting from said cylinder through the die, a punch carried by the rod, 40 and means for moving the rod to carry the punch into said die, said rod, cylinder and die placing said frame members under compression meanwhile.

45 In witness whereof, I hereunto subscribe my name this 4th day of February, 1930.
GEORGE SPATTA.
